ROTARY AIR ATOMIZING BURNER

Herman O. Grimmeisen, West Springfield, Mass.,
assignor to Gilbert & Barker Manufacturing
Company, West Springfield, Mass., a corpora-
tion of Massachusetts

Application May 3, 1947, Serial No. 745,760

4 Claims. (Cl. 158—77)

1

This invention relates to improvements in oil burners of the so-called air-atomizing type.

The invention has for its general object the provision of a burner which will burn fuel oil efficiently and safely, with a clean fire at starting and stopping, over a wide range of rates, from the very low rates required for the heating plants of small homes and for hot water heaters, to the high rates required for heating large buildings and for industrial purposes.

The invention has for a particular object the provision of an improved nozzle in which oil and air are efficiently mixed and from which the oil-air mixture is emitted in a spray to be mixed with more air and burned.

The invention has for another object the provision in a nozzle of the type described, of an arrangement for expelling residual oil from the nozzle passages after the oil feed has been cut off, the arrangement including revolving the nozzle to throw oil from the oil feed passages of the nozzle into the air passage from which it is swept out of the nozzle by a high velocity air stream and including also a bellmouth outlet flaring outwardly from the nozzle orifice and adapted to remove oil therefrom by centrifugal force due to the nozzle's rotation.

The invention has for another object the provision in an oil burner of an improved construction and arrangement of parts adapted for economical manufacture and for convenient servicing in the field.

The invention will be disclosed with reference to the accompanying drawings, in which,

Fig. 1 is a sectional elevational view of a burner embodying the invention;

Fig. 2 is a fragmentary cross sectional view taken on the line 2—2 of Fig. 1 and showing the constant level reservoir and oil control valves;

Fig. 3 is a front elevational view of the burner;

Fig. 4 is a cross sectional view taken on the line 4—4 of Fig. 1;

Fig. 5 is a fragmentary sectional elevational view, drawn to a larger scale and showing the oil and air supply conduits for the atomizing nozzle;

Fig. 6 is an enlarged sectional elevational view of the air-atomizing nozzle;

Fig. 7 is a fragmentary exterior elevational view showing the air control shutter and having parts broken away to show the mounting of the pump and fan housing on the burner casing;

Figs. 8 and 9 are cross sectional views respectively taken on the lines 8—8 and 9—9 of Fig. 1 and respectively showing the air control shutter and air pump;

Fig. 10 is a rear elevational view of the burner;

Fig. 11 is a wiring diagram illustrative of the burner control system; and

Fig. 12 is a sectional view of a timing motor used in the control system of the burner.

2

Referring to these drawings; the burner frame includes a horizontally-disposed tubular housing 1 (Fig. 1), suitably supported, as by the pedestal 2 and floor plate 3. The housing 1 affords a passage 4 for the supply of secondary or low pressure air. The rear (right hand) end of the housing 1 is made larger in diameter than the front and outlet end in order to receive a fan 5 located with its axis of rotation coincident with the axis of the air passage 4. Suitably secured to the rear end of housing 1, as by the multiple thread lock indicated at 6, is a housing 7 which has in its front face a hollow cylindrical recess 8 cooperating with the enlarged opening 9 in the rear end of housing 1 to form the housing for fan 5. The multiple thread lock is also shown in Fig. 7. The rear face of housing 7 is recessed to form a chamber 10 (Fig. 1) for a pump which supplies primary air to the atomizing nozzle of the burner. Secured to housing 7, as by screws 11 (Figs. 7 and 10), and closing the outer end of pump chamber 10 (Fig. 1) is a hollow housing 12. Secured to housing 12, as by screws 13 (Figs. 7 and 10), is a hollow end housing 14. These housings 12 and 14 (Fig. 1) afford within them oil-receiving chambers 15 and 16, respectively, separated by a suitable oil filter 17, which is clamped between the two housings. The burner frame further includes a bracket 18, which extends upwardly from the top of housing 1 and rearwardly thereof to support an electric motor 19, which as shown in Figs. 3 and 10 is secured to the bracket by cap screws 20.

Rotatably mounted and coaxially located with-in the housing 1 (Fig. 1) is a shaft 21, suitably supported, as by ball bearings 22 and 23. The bearing 22 is mounted in pump housing 7. The bearing 23 is mounted in a tubular housing 24, integrally connected by inclined blades 25 to an annular rim 26, which is slidably engaged with a cylindrical wall portion of passage 4. A pin 25' in housing 1 engages in a slot 28' in rim 26 to prevent the latter from turning. The blades 25 form a turbulator serving to whirl the air forced through passage 4 by fan 5. The fan 5 is fixed to shaft 21, as by the set screw 27. Keyed to shaft 21 (Fig. 5) is a driving pulley 28, which is held in axial position between a shoulder on the shaft and the inner race of bearing 22. The shaft 21 extends into the chamber 10 and has fixed thereto the rotor 29 of the air pump. This rotor and the inner race of bearing 22, both fixed to shaft 21, engage opposite faces of the bearing-supporting wall of housing 7 and thus hold the shaft against any substantial axial displacement therein. The drive pulley 28 is connected by a belt 30 to a pulley 31 fixed on the outer end of the shaft 32 of motor 19.

The shaft 21 serves to revolve the atomizing nozzle of the burner and contains within it the

Supply passages for air and oil. Referring to Fig. 6, the front end of shaft 21 is turned down and threaded, as at 33, to receive a cap 34, which forms the outer part of the nozzle and which engages a shoulder 35 on the shaft. This cap has a cylindrical inner wall 36 and a frusto-conical inner wall 37 which connects wall 36 to the outlet orifice 38 of the nozzle. This orifice has an outwardly flaring wall 38' forming a small spinning cup. The front end of shaft 21 forms the inner part of the nozzle. This shaft is turned down to provide a cylindrical part 39, a frusto-conical part 40, the outer surface of which closely fits the wall 37 of the nozzle cap, and two frusto-conical portions 41 and 42, each of different slope and of a slope different from that of wall 37. Between these frusto-conical portions 41 and 42 and the frusto-conical wall 37 is formed an annular venturi 43. A plurality of radial openings 44 connect the throat of the venturi to a central oil feed passage 45, which is formed in shaft 21 and leads from those openings rearwardly to a larger bore 46 in the shaft (the rod 48 and packing 50 is considered absent for the moment). This bore 46 extends to the rear end of the shaft as shown in Fig. 5. At the intersection of bores 45 and 46 is a square shoulder 47. A rod 48, having an axial passage 49 therethrough is pressed into bore 46 with its inner end pressing against an annular rubber gasket 50. The rod may be fixed to shaft 21 in any suitable way as by a set screw 48' (Fig. 5). The other end of rod 48 extends beyond shaft 21 and through a sleeve bearing 51 in housing 12 into the oil chamber 15. Oil may thus flow through passage 49, the hole in gasket 50, passage 45, and to and through the radial jets 44 into the throat of the annular venturi passage 43. The rod 48 has two longitudinal slots 52 at diametrically opposite locations in its external periphery. These slots are formed like keyways in a shaft and, when the rod 48 is in place in the bore 46, of shaft 21, these slots form passages for conducting air from the air pump to the atomizing nozzle. These slots 52 extend from the bearing 51 nearly to the front end of rod 48, terminating as shown in Fig. 6, just short of such end and communicating one with each of two inclined holes 53, formed in the threaded end of shaft 21 at diametrically opposite locations and opening into an annular chamber 54. This chamber communicates with the annular venturi 43 by means of a plurality of slots 55 formed in the frusto-conical part 40. These slots are inclined to the axis of revolution of part 40 so that air from chamber 54 will enter the annular venturi with a helical motion. The whirling air, as it advances in the annular venturi, increases in velocity until it reaches the throat of the venturi where it is met by oil ejected from radial passages 44 by the rotating inner part of the nozzle. The oil and air mix in the venturi forming an emulsion, which is allowed to expand as it advances, finally leaving the nozzle orifice in a finely atomized conical spray of air and oil. This spray meets and mixes with the whirling stream of secondary air which is forced by fan 5 through passage 4 and which is turned into the spray by the cone 56 (Fig. 1) on the outlet end of the air tube 1.

The combustible mixture of air and oil is ignited in any suitable way, as by an electric spark produced between a pair of electrodes 57 (Figs. 1, 3 and 4). These electrodes are mounted one in each of two insulating tubes 58, which are

suitably fixed as by set screws 59 (Fig. 4), in holes formed in the blades 25 of the air turbulator. The rear end of each electrode (Fig. 1) is upturned at right angles, as at 60, to engage a spring contact 61. These contacts 61 are fixed, one to each, of the high tension terminal conductors 62 of an ignition transformer contained within the casing 63. The base plate 64 of this casing is secured, as by screws 65, to posts 66 and to a boss 67 on housing 1. The conductors 62 extend from the transformer through depending insulators 68, the lower ends of which extend through the housing 1 into passage 4, bearing the terminals 61 on their lower ends. The arrangement enables axial separation, and electrical disconnection, of the electrodes from the high tension terminals of the transformer when the parts within the housing 1 are withdrawn for servicing, as hereinafter explained in detail.

The air pump may be of any suitable kind. One suitable form of pump is shown in Fig. 9. The rotor, which is located eccentrically of chamber 10, is radially slotted to slidably receive a plurality (six as shown) of blades 70. The ends of the blades lie flush with the end faces of the rotor. These end faces have cylindrical recesses 71 therein to receive, one in each, annular rings 72 upon which the ends of the blades rest and by which the outer edges of the blades are held engaged with the internal periphery of chamber 10. The inner ends of all the blades and the inner end face of rotor 29 engage the inner end wall of chamber 10 while the outer ends of all 30 the blades and the outer end face of the rotor engage the outer end wall of the chamber. The outer end wall of the chamber 10 is formed in part by a circular disk 73 set into a circular recess in the housing 12. The latter has a recess 74 35 in communication at one end with the outlet port 75 of the air pump and at its other end with the grooves 49 in rod 48. The inlet port 76 of the air pump communicates with one end of a passage 77 in housing 12 and into the other end of 40 this passage is set a suitable air filter 78. Thus, the air pump, when revolved, will draw in air through the filter 78, passage 77 and port 76 and force it out through port 75, into recess 74, slots 52 and passages 53 into the annular air chamber 50 54 of the atomizing nozzle.

Oil is supplied to the chambers 16 and 15 and thus to the nozzle feed passage 49 by gravity flow from a constant level reservoir 79 (Fig. 2) formed in a casing 80, secured as by screws 81, to a pad 82 on the casing of motor 19. The outlet 83 of this reservoir is connected by a pipe 84 to the inlet 85 (Fig. 1) of chamber 16. A valve 86 (Fig. 2) controls the outlet 83. This valve is fixed to the lower end of the plunger 87 of a solenoid contained in a casing 88. This casing is screw threaded into an annular casing 89, which is supported by legs 90 fixed to the bottom wall of the reservoir. The casing 88 has a serrated head 91 fixed to its upper end for convenience in turning the casing, when the cover 92 of the casing 80 is removed. The upward movement of the plunger 87, caused by energization of the solenoid is limited by the abutment of a collar 87' on the plunger with the bottom wall of the casing 88 of the solenoid. By raising or lowering the casing 88, the amount of lift of the plunger can be respectively increased or decreased to increase or decrease the amount of opening of valve 86 and 70 75 thus the rate at which oil will be fed under the

constant head to the atomizing nozzle of the burner. A spring 93, fixed at one end to a side wall of reservoir 80, has on its other end a fin to engage between successive serrations in the head 91 and hold the latter in any of the various positions of adjustment to which it may be moved. The valve 86 is held by gravity in closed position, when the solenoid is not energized.

Oil is supplied to reservoir 79 by means of a suitable pump 94 (Fig. 10) mounted on the end bell of motor 19 and driven by the latter. The inlet of this pump is adapted to be connected by a pipe, such as is shown in part at 95, to a low-level, oil-supply reservoir (not shown). The outlet of pump 94 is connected by a pipe 96 to the reservoir 79 (see also Fig. 2). The latter contains a float 97, suitably guided as indicated and carrying a valve 98 to control a second outlet 99 from the reservoir. Outlet 99 is connected by a pipe 100 to the suction pipe 95 (Fig. 10) of the oil pump. The pump will supply oil to reservoir 79 at a rate at least equal to, and usually slightly in excess of, the maximum rate at which oil may be used by the burner, as controlled by the adjustment 91 of valve 86. When the pump 94 is in operation, the float 97 will rise and open valve 98 to by-pass part of the pumped oil through pipe 100 back to the suction side of the pump. In this way, oil is maintained at a constant level in the reservoir and a fixed head of oil is maintained for the gravity flow of oil to the atomizing nozzle.

Oil fed into the chamber 15 is prevented from flowing into the air pump by means of a seal ring 101 (Fig. 5), mounted on and rotating with rod 48 and pressed into sealing engagement with the flanged end face of sleeve bearing 51 by means of a coil spring 102. This spring acts against a washer 103 held in place by a snap washer 104, engaged in a circumferential groove in rod 48 near its outer end.

The rate at which secondary air is supplied through the air passage 4 to the atomizing nozzle is controlled by an air shutter comprising an arcuate band 105 (Figs. 7 and 8) mounted in a circumferential groove in the exterior peripheral portion of housing 7. Such portion has air inlet ports 106 (Fig. 8) in addition to the hole 107 through which belt 30 extends into the fan housing. The shutter is held in place by two screws 108, each passing through a slot 109 (Fig. 7) in band 105 and threaded into the housing 7. When the screws 108 are loosened, the band 105 may be moved by a handle 110 to increase or decrease the effective area of the ports 106. This is done by a slot 108' in the band moving nearer to or farther from a position of registration with the right hand port 106 shown in Fig. 8 and by the left hand end of the band overlapping the other port 106 to a lesser or greater extent as the case may be.

The bearing 23 for the rotatable, nozzle-carrying shaft 21 is protected from the heat reflected back in the passage 4 from the flame produced by the burner by a shield 111 (Figs. 1 and 5). This shield comprises a tubular extension of the bearing housing 24, which extension closely encompasses shaft 21 and extends a substantial distance toward the nozzle. The bearing is also cooled by air picked up by the cup-like outer end 112 of the bearing housing. A stream of air is forced through the bearing, leaving by the small annular passage 113 between the shield 111 and shaft 21. When the burner stops and the flow of cooling air ceases the shield 111 will keep the heat reflected back into passage 4 from reaching the bearing.

The controls for the burner may be contained in a box 114, secured to a pad on the motor 19, as indicated in Figs. 1 and 3.

A control system for the burner is shown diagrammatically in Fig. 11. This system is arranged to start the burner motor 19 by a room thermostat switch 115 on a demand for heat from the burner but the flow of oil to the burner is delayed until the motor 19 has acquired full speed so that the atomizing nozzle, the air pump, and the air fan 5 are all rotating at full speed before oil reaches the nozzle. After the demand for heat is satisfied, the room thermostat switch 115 opens and the flow of oil to the nozzle is stopped but the motor 19 is continued in operation for a time after the oil flow has ceased. The arrangement avoids smoky operation during the intervals in which the motor 19 with the nozzle, air pump and air fan 5 are accelerating or decelerating.

The time delay of the opening of the oil valve on starting and the time delay of the stopping of the motor 19 after closing of the oil valve on stopping are effected by the use of a timing shaft 116, which is driven by an electric motor and operates a switch 117, controlling certain circuits to be later described. This timing motor may be of any suitable type. One such type is shown in Fig. 12. It is a self-starting, single-phase, synchronous motor of the shaded pole type of the kind disclosed in U. S. patent to Haydon No. 1,996,375, dated April 2, 1935, to which reference may be had for a more complete disclosure, if necessary or desired. Briefly, the motor includes a field winding 118 adapted for connection to a 110 volt, alternating-current, supply circuit and mounted on a magnetizable core 119, the ends of which carry magnetizable disks 120 and 121, bearing the pole pieces of the motor. The rotor 122 is fixed to the outer end of a shaft 123 which is rotatably mounted in bearings within the tubular core 119 and which carries on its inner end a driving pinion 124. The rotor shaft and pinion are also bodily movable in an axial direction to move the pinion into and out of mesh with one terminal gear 125 of a train of gears 126. The other terminal gear of the train is shown at 127, fixed to the timing shaft 116. A spring 128 acting between the outer end of core 119 and rotor 122 tends to hold the rotor, with its shaft 123 and pinion 124, in the extreme right hand position shown, in which the pinion 124 is disengaged from gear 125 and abuts the inner end of core 119. When the field winding 118 is energized, core 119 and disks 120 and 121 are magnetized and the magnetic pull from disc 120 and core 119 draws rotor 122 to the left, compressing spring 128 and moving pinion 124 into mesh with gear 125. The rotor will also be rotated which will through the gear train described, rotate the timing shaft 116 clockwise, as viewed in Figs. 11 and 12. The shaft 116 may, for example, turn at the rate of 1 revolution per minute. It turns clockwise until a stop 129 (Fig. 11) on the shaft 116 is arrested by abutment with the right hand side of a stationary stop 130. The shaft then remains stationary as long as the winding 118 is energized. When this winding is deenergized, a spiral spring 131, which was wound up by the clockwise rotation of the shaft, will turn the shaft 116 counterclockwise back to its initial position illustrated, in which the stop 129 engages the left hand side of the stop 130. When the motor winding 118 is deenergized, the axial magnetic pull on the rotor 122 ceases and spring 128 will pull shaft 123 to the right, drawing pinion 124 out

of mesh with gear 125 and allowing spring 131 to turn the timing shaft and gear train backwardly as described.

The room thermostat switch 115 is arranged in a low voltage circuit supplied by the secondary 132 of a transformer, the primary 133 of which is connected by wires 134 and 135 to the supply wires 136 and 137, respectively, of a suitable source of electric supply, such as a 110 volt A. C. supply. The low voltage room thermostat circuit includes, in addition to switch 115 and secondary 132, the coil 138 of a relay, an electric heating coil 139, a thermostat switch 140 adapted to be heated by coil 139 and wires 141, 142, 143, 144 and 145, which connect these elements in series. When the switch 115 closes on a demand for heat from the burner, the relay coil 138 is energized and this causes the closing of a switch 146.

The switch 146 controls a circuit to the winding 118 of the timing motor and a starting circuit for the burner motor 19. The circuit to the winding 118 may be traced as follows: from supply wire 136 by wire 147, switch 146, wires 148 and 149 to winding 118 and thence by wire 150 to supply wire 137. The starting circuit for the burner motor 19 may be traced as follows: from supply wire 136, by wire 147, switch 146, wires 148, 151 and 152, engaged switch contacts 153 and 154, wire 155 to motor 19 and thence by wires 156 and 150 back to supply wire 137.

The switch contact 154 and another contact 157 are movable by a relay coil 158, when energized, into engagement with contacts 159 and 160, respectively. This relay coil 158 is controlled by the switch 117 in a circuit which may be traced as follows: from supply wire 136, by wire 161, switch 117, wire 162 to relay coil 158 and thence by a wire 163 to wire 156, up wire 156 to wire 150, and wire 150 back to supply wire 137. The switch 117 is adapted to be closed by a cam 164 on timing shaft 116 after this shaft has revolved for say 20 seconds and the switch is then held closed for the remainder of the clockwise travel (say 30 seconds) of shaft 116. The closing of switch 117 causes relay coil 158 to be energized and this in turn causes the switch contact 154 to leave stationary contact 153 and engage stationary contact 159.

One effect of the closing of this relay switch is to remove the burner motor 19 from control by room thermostat switch 115 and place it under the control of relay 158 and the switch 117 driven by timing shaft 116. The motor 19 is now in a running circuit which may be traced as follows: from supply wire 136, by wire 165, engaged contacts 159 and 154, wire 155 to motor 19 and thence as before by wires 156 and 150 back to supply wire 137. The opening of relay switch 146 will not cause motor 19 to stop immediately but only after the timing shaft 116 has been moved back far enough to allow switch 117 to open and this may take, say 30 seconds.

The contacts 157 and 160, which are also engaged on energization of relay coil 158, control the solenoid 166, which when energized, opens the valve 86 and allows oil to flow to the atomizing nozzle of the burner. The circuit for solenoid 166 may be traced as follows: from supply wire 136 by wire 147, switch 146, wires 148 and 151, engaged contacts 157 and 160, wire 167 to solenoid 166 and thence by wire 168 to wire 156, up wire 156 to wire 150 and by wire 150 back to supply wire 137.

On occurrence of combustion, a burner thermostat switch, such for example as a stack switch closes and prevents the safety switch 160 from

opening. The stack thermostat switch is indicated at 169 and its terminals are connected by wires 170 and 171 to the terminals of the electric heating coil 139. Closure of switch 169, on occurrence of combustion at the burner, shunts out the heating coil 139 and stops the heating of the bimetallic element of switch 140. This switch, if heated for say 90 seconds would open and stop the burner. However, if combustion occurs within the interval of 90 seconds, the switch 169 will be closed and the heating effect on switch 140 will be stopped before switch 140 can open. The arrangement described is the usual combustion safety control. It functions here a little differently than in the ordinary burner control system in that opening of switch 169 on failure of combustion does not immediately deenergize the burner motor 19. The flow of oil to the burner is immediately cut off by the closing of valve 86 on the deenergization of solenoid 166 and the timing motor is deenergized but the motor 19 continues to run until the timing shaft has been turned backward far enough to allow switch 117 to open. Thus, the burner motor and the air pump, air fan and atomizing nozzle will be rotated for a substantial time interval, say 30 seconds after the oil flow has been cut off.

In operation, on a demand for heat from the burner, the room thermostat switch 115 closes and this causes closure of the relay switch 146, which in turn closes a circuit to the winding 118 of the timing motor and a starting circuit for the burner motor 19. The latter starts the air pump, air fan and atomizing nozzle and these elements are in rotation at full speed before oil is supplied to the nozzle. The timing shaft 116 starts to turn coincidentally with the burner motor and after it has been turning for about 20 seconds, switch 117 closes and causes energization of relay coil 158, which in turn causes the closing of a circuit to solenoid 166, whereby the oil valve 86 is opened. Oil now flows to the atomizing nozzle and mixes with the air as described in detail hereafter and the combustible mixture is ignited and burns, causing heat to be supplied to the rooms needing heat. The energization of relay 158 also opens the starting circuit for the burner motor 19 by separation of the contacts 153 and 154 and establishes a running circuit by the closure of contacts 154 and 159, which running circuit is under the control of relay 158 and thus of switch 117. When the demand for heat is satisfied, the room thermostat switch 115 opens, and this causes switch 146 to open, deenergizing the solenoid 166 and causing the oil valve 86 to close and stop flow of oil to the burner and also deenergizing the timing motor and allowing the timing shaft 116 to turn backwardly. After this shaft has turned backwardly for say 30 seconds, switch 117 will open to cause deenergization of relay coil 158 and the separation of contacts 157 and 160, 154 and 159, which deenergizes the burner motor, and the engagement of contacts 154 and 153 to reestablish a starting circuit for the burner motor under control of relay switch 146. It will thus be seen that full air flow and full rotation of the atomizing nozzle are established for a substantial time interval before oil is allowed to flow to the atomizing nozzle. The switch 117 closes 20 seconds after the timing motor and burner motor are simultaneously energized and in a second or two after its energization the burner motor will be operating at full speed. Likewise on stopping, the air flow and rotation of the nozzle will be continued at full speed for say

30 seconds after oil flow has ceased. These provisions avoid smoky combustion, during the interval while the burner motor is accelerating, by delaying the admission of oil until the motor 19, fan, air pump and atomizing nozzle have acquired full speed and, during the interval when the motor is decelerating, by cutting off the flow of oil to the nozzle well before the circuit to the burner motor is opened.

In the operation of the atomizing nozzle, on a demand for heat, the motor 19 is immediately started to drive the air pump, fan and nozzle. In a very brief time, say about one second, these elements will be rotating at full speed and, soon thereafter, the pump will have established flow of air through the nozzle and flow of air through passage 4 outside of the nozzle at the desired rates. The air fed into chamber 54 by the air pump is forced through the slots 55 and caused to whirl as it enters the annular venturi passage 43. As the whirling air streams advance in this venturi, their velocity increases until they reach the throat of the venturi. Subsequently, the velocity is reduced somewhat as the air streams advance to the end of the venturi and issue from the nozzle orifice 38. After the described air flow has been established within the nozzle and the whirling air flow has been established through passage 4 outside of the nozzle, the solenoid valve 86 is opened and oil allowed to flow from the constant level reservoir. Oil advances, under gravity head, through the central oil passage 49, 45 and, when oil reaches the end of passage 45, it is thrown outwardly through radial passages 44 by centrifugal force aided also by the suction effect created by the rush of air at high velocity through the throat of the venturi across the outer ends of passages 44. The jets of oil, issuing into the whirling air stream moving at maximum velocity through the throat of the venturi, mix with the air and form an emulsion. This emulsion advances through the venturi and the mixing of air and oil continues as the mixture progresses and expands. The emulsion leaves the venturi and enters the outlet orifice 38, expanding in a conical spray. This spray is met by the whirling air stream outside the nozzle, which stream is directed into the spray by cone 56 and caused to mix therewith. The combustible mixture is ignited by a spark produced between the electrodes 57 and combustion occurs and continues until the demand for heat is satisfied. The solenoid valve 86 closes on the opening of thermostat switch 115 and the oil flow is immediately cut off. However, air continues to flow through the nozzle and outside the nozzle for a time to avoid smoky combustion. The oil remaining in the passages 44 will be thrown outwardly into the venturi by centrifugal force and such oil will be carried forward through the venturi by the rushing air stream and discharged through orifice 38. Any oil remaining on the outwardly flaring wall 38' will be thrown outwardly by centrifugal force and discharged by the knife edge terminus of the wall. The effect is to clean the surface 38' free of oil film and leave nothing there to carbonize from the heat reflected back on the nozzle from the hot walls of the combustion chamber after combustion has stopped. The continued movement of air at high velocity through the venturi, after the oil flow has been cut off, has the effect of wiping the walls of the venturi free of oil film. The nozzle is thus cleaned of oil back to the passage 45. In particular, the narrow passage of the venturi, the small

orifice 38 and its cup like discharge mouth 38' are cleaned of oil to avoid carbonization and the resulting clogging of the nozzle passages from soot and the depositing of soot on the wall of cup 38'. The continued flow of air after cessation of oil flow, tends to cool the nozzle at a time when it is most needed to counteract the effect of reflected heat from the combustion chamber. Also, the latter is thoroughly scavenged and to some extent cooled. There is never a time when oil can issue from the nozzle without meeting air streams moving at the rate necessary for complete combustion at full rate of oil flow. Consequently, smoky operation during acceleration and deceleration of the rotating parts, is avoided.

The invention also offers a compact and simple arrangement of parts, calculated to enable quantity manufacture of the burner at low unit cost. All parts of the burner are also easily accessible for convenient servicing and are easily replaced, when required. By removing the belt 30 from pulley 31, disconnecting oil pipe 84 at the union which connects it to the outlet 83 of the float chamber, and by turning the housing 7 a third of a revolution to unlock it from the main housing 1, the unit, comprising the housings 7, 12 and 16, the atomizing nozzle, electrodes 57, turbulator 25 and fan 5 may be withdrawn from the interior of housing 1, while maintained assembled in working relation. The act of withdrawing these parts, automatically disconnects the electrodes 57 from the high voltage terminals 61 of the transformer. The air filter 78 can readily be removed for servicing. The oil filter 17 can readily be removed for cleaning by disconnecting the housing 14 from housing 12. Should access to the air pump be required, it can be had by disconnecting the housing 12 from housing 7. The aforesaid unit may be replaced in housing 1 by first inserting the nozzle 34, shaft 21, electrodes 57, and the turbulator 25, part way into the housing until the leading end of projecting part of rim 26, having the slot 26', is about opposite the pin 25'. A substantial space will then be left between the adjacent ends of housings 1 and 7. The operator inserts his fingers through this space and turns the turbulator until the slot 26' and pin 25' are aligned and then he pushes forwardly on the turbulator enough to engage the pin in the front end of the slot. The operator then withdraws his fingers from the interior of housing 1 and thrusts housing 7 inwardly to close the aforesaid space after which he turns the housing 7 to engage the multiple threads and lock the housing 7 to housing 1. The belt 30 is replaced on pulley 31 and the burner is ready to operate. For regulating the flow of combustion-supporting air through the passage 4 after the parts are again assembled in working relation, the air shutter 105 is accessible from outside the burner and may be moved by handle 110 after screws 108 have been loosened. The rate of oil flow may be regulated by adjustment of solenoid casing 88, effected by turning member 91 after the cover 92 of the constant-level, oil-supply reservoir has been removed.

The invention thus affords an improved oil burner of the air-atomizing type, which, while applicable generally, is especially suitable for use where low rates of oil flow are required, such as for heating small homes and for hot water heaters. Relatively large oil passages can be used at the low rates of oil flow without clogging because of the flow of air as well as oil through the nozzle orifices. And sootless operation during the peri-

11

ods of acceleration and deceleration of motor, air pump, and fan is insured by the arrangement described for preventing the admission of oil on starting up the burner until full air flow has been established at the atomizing nozzle and by stopping the oil flow before the motor which drives the air pump and fan, is cut off, whereby air flow at the nozzle is continued after oil flow has ceased to scavenge the combustion chamber.

I claim:

1. In an oil burner, a shaft having therethrough a central oil conduit and an air conduit, means for rotating said shaft, an atomizing nozzle fixed to one end of said shaft, said nozzle comprising a hollow outer member having a hollow cylindrical part intersecting at one end with a hollow conical part which terminates with a small discharge orifice, and an inner member having a cylindrical part closely fitting the other end of the hollow cylindrical part of the outer member and provided with air and oil passages therethrough respectively communicating at one end with the air and oil conduits in said shaft and closing the other end of the hollow cylindrical part of the outer member except for said air and oil passages, said inner member having a conical part located in spaced and coaxial relation with the first-named conical part, said conical parts forming between them an annular venturi leading to the discharge orifice, said venturi in longitudinal section converging from its entrance end to a throat and diverging from the throat to said orifice, said air and oil passages respectively communicating at their other ends with the entrance end and throat of said venturi, means for supplying oil to the oil conduit in said shaft, and means for supplying high pressure air to the air conduit in said shaft.

2. In an oil burner, a shaft having therethrough a central oil conduit and an air conduit, means for rotating said shaft, an atomizing nozzle fixed to one end of said shaft, said nozzle comprising a hollow outer member having a hollow cylindrical part intersecting at one end with a hollow conical part which terminates with a small discharge orifice, and an inner member having a cylindrical part closely fitting the other end of the hollow cylindrical part of the outer member and provided with air and oil passages therethrough respectively communicating at one end with the air and oil conduits in said shaft and closing the other end of the hollow cylindrical part of the outer member except for said air and oil passages, said inner member having a conical part located in spaced and coaxial relation with the first-named conical part, said conical parts forming between them an annular venturi leading to the discharge orifice, said venturi in longitudinal section converging from its entrance end to a throat and diverging from the throat to said orifice, said air and oil passages respectively communicating at their other ends with the entrance end and throat of said venturi, means for supplying oil to the oil conduit in said shaft, and means for supplying high pressure air to the air conduit in said shaft, said discharge orifice terminating with an outwardly-flaring frusto-conical wall for slingng outwardly by centrifugal force any oil thereon.

3. In an oil burner, a shaft, a nozzle fixed to one end of said shaft and comprising inner and outer members forming between them an annular passage converging from one end of large diameter to another end of small diameter, the small end of said passage terminating with an outlet ori-

12

fice formed in said outer member, said annular passage in longitudinal section converging from its large end to a narrow throat located intermediate its ends and then diverging toward its other and small end, the inner member having a central oil passage and a circular series of branch passages connecting one end of the central passage to the throat of the annular passage at a plurality of angularly spaced points, a high-pressure air pump, means including a conduit in said shaft for connecting the pump to the large end of said annular passage, means including a conduit in said shaft for feeding oil to the other end of said central oil passage, means for rotating said shaft and nozzle and for actuating the high pressure air pump, and means for starting and stopping the oil feed to the oil conduit in said shaft operable to stop such oil feed before the shaft-rotating means and air pump actuating means are stopped, whereby to purge the nozzle by the action of centrifugal force in throwing the oil out of said branch passages into the throat of said annular passage and by the discharge of high pressure air through the annular passage and outlet orifice to sweep the oil therefrom.

4. In an oil burner, a shaft, a nozzle fixed to one end of said shaft and comprising inner and outer members forming between them an annular passage converging from one end of large diameter to another end of small diameter, the small end of said passage terminating with an outlet orifice formed in said outer member, said outer member having an outwardly-flaring frusto-conical wall forming a cup surrounding said orifice and receiving oil therefrom, said annular passage in longitudinal section converging from its large end to a narrow throat located intermediate its ends and then diverging toward its other and small end, the inner member having a central oil passage and a circular series of branch passages connecting one end of the central passage to the throat of the annular passage at a plurality of angularly spaced points, a high-pressure air pump, means including a conduit in said shaft for connecting the pump to the large end of said annular passage, means including a conduit in said shaft for feeding oil to the other end of said central oil passage, means for rotating said shaft and nozzle and for actuating the high-pressure air pump, and means for starting and stopping the oil feed to the oil conduit in said shaft operable to stop such oil feed before the first-named means is stopped, whereby to purge the nozzle by the action of centrifugal force in throwing the oil out of said branch passages into the throat of said annular passage and by the discharge of high-pressure air through the annular passage and outlet orifice to sweep the oil therefrom, said cup by its rotation after the flow of oil is cut off slingng off by centrifugal force any oil deposited thereon during the purging of the nozzle passages.
